UNITED STATES PATENT OFFICE.

HARRY E. SIPE, OF NEW YORK, N. Y.

LOCK STRIP OR BODY.

Application filed September 16, 1927. Serial No. 220,050.

This invention relates to lock strips or bodies for use in fixedly and yieldably retaining or coupling two or more parts together to prevent the separation or uncoupling of said parts without the use of bolts, screws, rivets or other devices; and the object of the invention is to provide a strip or body of the class described consisting of a plurality of comparatively narrow 5 as well as comparatively thin sheets, laminations or segments of paper, paper board, fibre, metal, rubber, wood or similar material, arranged in a face to face relation with the side edges of said sheets or strips exposed at opposite sides of the lock strip or body and adapted to engage the surfaces or faces of the parts to be coupled together; a further object being to provide a strip or body of the character above set out wherein 10 the separate sheets, strips or segments of the device may constitute independent parts arranged in abutting relation or may consist of a single body of the several materials referred to folded upon itself a number of 15 times to arrange segmental portions thereof in a face to face and compact relation; and still further to a body wherein one side or both side faces of which are segmented by slots, cuts or the like; a further object being 20 to provide a lock device of the class specified wherein the separate parts or segments thereof may be composed of different materials, alternately arranged throughout said body and wherein one of the materials employed may be substantially of rigid character and the other of yielding, elastic or resilient qualities; a still further object being 25 to provide means whereby the lock strip or body may be retained in different positions 30 with relation to at least one of the parts to be coupled together thereby; a still further object being to provide a lock strip or body structure wherein the separate segments or parts are disposed angularly with relation to each other at opposite sides thereof for 35 retaining the parts coupled together thereby against lateral as well as end-wise movement; and with these and other objects in view, the invention consists in the method 40 herein described for coupling parts together, and in the device for carrying said method into effect, hereinafter more fully described and claimed.

The invention is fully disclosed in the following specification, of which the accompanying drawing forms a part, in which

the separate parts of my improvement are designated by suitable reference characters in each of the views, and in which:—

Fig. 1 is a sectional, detail view showing 60 one method of coupling two metallic frame parts together.

Fig. 2 is a sectional, plan view of a structure similar to that shown in Fig. 1 but showing a modified form of lock strip construction. 65

Fig. 3 is a view similar to Fig. 1 but showing a different method of coupling metallic bodies together.

Fig. 4 is a view similar to Fig. 1 and 70 illustrating the method of coupling a bracket part to the frame part.

Fig. 5 is a detail view of one form of lock strip which I employ.

Fig. 6 is a side view of the structure shown 75 in Fig. 5.

Figs. 7 to 12 inclusive, are views similar to Fig. 5 but showing other forms of lock strips.

Fig. 13 shows a modified use of my improved strip as an expansion joint between 80 two sheets or slabs.

Fig. 14 shows a method of retaining a panel in a body of any kind or class by the use of my improved strip. 85

Fig. 15 is a detail view of another form of lock strip which I employ.

Fig. 16 is a view of the strip shown in Fig. 15 illustrating the method of its formation. 90

Fig. 17 shows transverse, sectional and side and sectional views of a method of coupling two abutting parts together by my improved lock strips.

Fig. 18 shows the method of coupling two 95 parts or bodies together by a modified form of strip.

Fig. 19 shows means for supporting and retaining a lock strip in predetermined position in one of the parts to be coupled together thereby. 100

Fig. 20 shows side and plan views of another form of lock strip; and,

Figs. 21 and 22 are detail views of other modified forms of lock strips. 105

In carrying my invention into effect I provide a locking strip or body having one or more segmental or laminated surfaces formed either by the assemblage of a multiplicity of leaves, segments, parts, or by incisions or grooves cut in one or both side faces of a body, or by folding a sheet upon itself a 110

number of times so that the exposed edges formed thereby are segmental.

In the use of the strip or body, the flexible or yieldable segments or parts thereof are normally arranged at right angles to the surfaces to be coupled together or at a slight angle of inclination, and are forced into an opening or space between the parts which is less than the vertical dimensions of the lock strip or body, whereby the segments or parts are flexed backwardly away from the direction of engagement in sliding the two parts together in the operation of coupling the same, thus moving said segments, laminations or parts into a slight angle with reference to the engaged surfaces, at which angle the segments form a series of wedges which resist return movement by edgewise stability and crushing strength of the segments and the lock strip or body as a whole, it being understood that suitable means will be provided for supporting, at least temporarily, the lock strip or body in engagement with one of the parts to be coupled together, and this may be done by slightly grooving one of said parts.

It will be understood that my improved lock strip is adapted for use in coupling two or more bodies of any kind or class together, regardless of the nature, texture or material employed in said bodies. In the accompanying drawing, I have shown, for illustrative purposes, only a few methods of carrying my invention into effect, and while I disclose one or more forms of lock strip in the several uses described, it will be understood that any form of lock strip disclosed or coming within the scope of my invention may be employed in the many uses thereof.

In Fig. 1 of the drawing, I have shown at 23 a frame member composed of channel iron which may constitute a frame member of apparatus of any kind or class, or the structural frame of a building or other body or steel structural assemblage. At 24, I have represented another metallic or other body coupled with the body 23 by placement within the channel thereof and by the use of substantially rigid lock strips *a* arranged at the inner end of the body 24 and other more flexible lock strips *b* arranged outwardly of the strips *a*. The strips *a* and *b* are arranged on the upper and lower surfaces of the body 24 and operate upon the inner faces of the top and bottom flanges 23^a and 23^b of the frame part 23. With this construction, a pad *c* of cushioning material is placed at the inner end of the body 24 to allow for the firm engagement of said parts 23 and 24, and the movement of the lock strips *a* and *b* from a position at right angles to their adjacent surfaces to a slight inclination as seen in the drawing, thus preventing backward movement or separation of the parts 23 and 24. In the construction de-

scribed, the strips *a* may be composed of metallic segments to form a strong and durable connection where the greatest strength of the parts coupled together is desired, whereas the strips *b* may be composed of more yielding and resilient material such as paper, cardboard, fibre, rubber and the like or a combination of such materials and metal. In coupling the parts together, the strips *a* and *b* may be retained in connection with either parts 23—24, preferably the part 23, by a suitable glue which will temporarily retain the parts in position to permit of the coupling of the body or part 24 with the frame part 23. It will also be understood that while I have described the part 23 as being composed of steel, it may be metal of any nature or structure whatever.

In Fig. 2 of the drawing, I have shown a modification, wherein the parts 23 and 24 are coupled together by pairs of lock strip sections *d* and *e* arranged on the upper and lower surfaces of the part 24 in the same manner as the arrangement of the strips *a* and *b* but the section *d* is composed of a plurality of segmental lock strips *d*² arranged at an angle of substantially forty-five degrees to the longitudinal plane of the part 24, where the section *e* has a series of similarly arranged lock strips *e*², the angle of inclination of which is opposed to that of the section *d*. With this construction, side-wise or lateral movement of the parts 23 and 24 with relation to each other is obviated, as well as endwise movement of the part 24 with relation to the part 23.

In Fig. 3 of the drawing, I have shown two angle iron parts 25 and 26 coupled together by two lock strips *f*—*f*² arranged on the outer faces of the flanges 25^a and 26^a of the parts 25 and 26 and within a U-shaped keeper or clamp 27. Arranged between the adjacent faces of the flanges 25^a and 26^a are two rubber pads 28—28^a between which is disposed a sheet metal retaining member 29 having side flanges 29^a which operate in conjunction with the rubber sheets 28—28^a to retain the parts 25 and 26 against lateral movement and to provide a friction coupling between said parts. In this form of construction, it will be understood that the lock strips *f* and *f*² will be made to compensate for the compression and resiliency of the rubber strips employed.

In Fig. 4 of the drawing, I have shown a bracket 30 coupled with a channel frame body 23 similar to that shown in Figs. 1 and 2, by means of a U-shaped keeper or clamp 27 similar to the clamp shown in Fig. 3. In this construction, one lock strip *f*³ is arranged between the lower flange 23^b of the frame and one side of the clamp 27, and another lock strip *f*⁴ is arranged between the other side of the clamp and the end face of the bracket 30. A pad of rubber or other

resilient material 28^b is arranged between the upper face of the bracket 30 and the flange 23^b.

In Fig. 13 of the drawing, I have shown 5 resilient segmental strips preferably arranged in a plurality of sections *g* disposed between adjacent edges of two boards, slabs or parts 31 and 31^a which may be mounted in connection with a suitable support 32. In 10 this use of my invention, the strips *g* operate as joints filling the space between the parts 31, 31^a and forming expansion joints therebetween. One illustration of this invention would be the provision of such joints between 15 wall boards or slabs used in building construction, but of course, many other uses may be made thereof. The resilient segmental strips arranged in the sections *g* are of a width greater than the width of the 20 space between the parts or wall boards 31 and 31^a, and of a thickness equal to the thickness of said boards. The sections *g* are placed in position by sliding the same downwardly over the wall or support 32 and between 25 the boards 31 and 31^a, and in this operation the separate strips of said sections flex upwardly at their ends, and in this manner compensate for any expansion or contraction that may exist between the boards 30 31 and 31^a.

In Fig. 14, I have shown lock strips *h* disposed between the side or peripheral edges of a panel 33 mounted in a frame 33^a for retaining the panel 33 against displacement. 35 In this use of the invention, the panel 33 may constitute a mirror, glass or a wood, metallic or other body of any kind or class, it being understood that the panel 33 seats on a back wall or flange portion 33^b limiting 40 its inward movement, and is checked against outward movement by the lock strips *h* employed.

In Fig. 17 of the drawing, I have shown 45 two metallic frame members 34 and 34^a employed in common abutting or endwise relation. In the construction shown, said frame members are of I-beam cross sectional form as seen in the cross sectional view in said figure. In this construction, a coupling 50 member 34^b encircles the frame parts 34 and 34^a whereby they abut, and coupling strips *i* are arranged between the outer and inner surfaces of the top and bottom flanges of the parts 34—34^a and the corresponding 55 surfaces of the coupling 34^b as clearly seen in both views of said figure. The angular arrangement of the strips is shown in the figure to the right, the strips *i* engaging the frame part 34 being at an angle opposite to that of the strips engaging the frame part 34^a, thus preventing endwise separation of the parts.

In Fig. 18 of the drawing, I have shown 60 a body 35 of any kind or class coupled with a channel body or frame 23 by providing

the end of the body 34 with a lock strip structure *h* secured in any desired manner to the end of said body 35 and projecting at opposite faces thereof to form flexing portions *h*² which engage the inner faces of 70 the top and bottom flanges 23^a and 23^b in coupling the body 35 with the frame part 23.

In Fig. 19 of the drawing, I have shown 75 a lock strip *m* mounted in a recess 36 in a part 36^a adapted to be coupled with a channel frame 23. In this construction, the lock strip *m* is retained in definite relation with reference to the part 36^a and flexes with relation to both parts in coupling the same together. It will be understood that the 80 depth of the recess 36 may be very shallow in many uses of the invention, and contrasting to that shown in said figure and especially in sheet metal structural work.

In the several uses of the invention herein disclosed, as well as in many other uses of the invention in coupling two parts or bodies of any kind or class together, it will be understood that I may employ any one of the coupling strips bodies or segments herein 90 disclosed, or coming within the scope of my invention, and where the reference characters *a* to *m* inclusive are given, it will refer to any one of my improved coupling devices that may be suited for the purpose intended. 95

A few forms of these devices are shown in Figs. 5 to 12 inclusive, 15, 16, 20, 21 and 22.

In Figs. 5 and 6 of the drawing, I have shown one form of lock device 37 which is composed of a unit body, the opposite side 100 faces of which are cut or subdivided longitudinally to form a plurality of resilient segments 37^a. As seen in Fig. 6 of the drawing, these segments are again divided by widely spaced transverse cuts 37^b to divide said segments into transverse rows 37^c. It will be understood that the body 37 may be composed of rubber, paper or any other suitable material. The central portion of the body will operate as a binder, retaining 110 the segmental side portions together.

In Fig. 7 of the drawing, I have shown a lock strip or device 38 which is composed of a plurality of comparatively thin strips, sheets or segments which may be of any 115 desired length, depending upon the specific use of the device and stacked into a desired width. It will also be understood that the depth of the respective segments may be arranged to suit the particular use thereof.

If desired, these segments may be retained in stacked relation by a binding strand or strip 38^a. Each strip segment or part of the device 38 may be composed of metal, wood, fibre, paper, rubber or any other desired material, or a combination of such materials, or an alternate arrangement of different materials may be employed, for 125 example as seen in Fig. 11 of the drawing, wherein a device 39 is provided with seg-

ments 39^a composed of one material, and intermediate segments 39^b composed of other material, for example, the segments 39^a may be composed of substantially rigid material such as metal, fibre and the like, and the intermediate segments may be composed of felt, rubber or other more yielding material. As seen in Fig. 12 of the drawing, a lock device 40 may be constructed of the same or different segments 40^a and 40^b arranged in alternate relation, the segments 40^b being of less depth than the segments 40^a to provide for a greater flexing of the exposed edges of the segments 40^a.

15 In Figs. 15 and 16, I have shown a lock device which is made from a sheet 41 of material folded at 41^a and 41^b in opposite directions, to bring the side faces of the strip adjacent each other in a compact body as 20 partially indicated in Fig. 15. The sheet 41 may be composed of paper, metal, rubber or other suitable material. When in its compact state, the folded edges will be exposed for engagement with the surfaces of 25 the parts to be coupled together.

In Fig. 8 of the drawing, I have shown one side face of a body 42 divided by cuts, serrations or the like 42^a into comparatively heavy segmental parts 42^b which are adapted 30 to engage a surface of the two parts to be coupled together, and one side edge of the segments 42^b are preferably beveled as seen at 42^c to allow for a greater flexing of the parts. As seen in Fig. 9, a body 42 similar 35 to that shown in Fig. 8 may also be subdivided by transverse cuts 42^d to give greater flexibility to the segments subdivided by said cuts 42^d. As seen in Fig. 9, the exposed surface of the segmented part of the device 40 may be arc-shaped in form as seen at 42^e to fit and operate upon arc-shaped surfaces. This may be true in all of the forms of lock 45 devices herein shown and described.

In Fig. 10 of the drawing, a body 43 is 45 subdivided and fashioned on its opposite side faces to form segments or parts 43^a, the exposed surfaces of which are beveled at opposite sides to form grooves or depressions 43^b between the separate segments 50 which allow for the greater flexing and displacement of the material of the segments or employed in the construction of the device 43, as will be apparent. The structure shown in Figs. 8, 9 and 10 is primarily 55 adapted for use in constructing lock devices from rubber or other resilient elastic bodies.

In Fig. 20 of the drawing, I have shown 60 at 44 another form of lock device consisting of a plurality of corrugated sheets or segments 44^a of metal, fibre or other material, between which is disposed strips or sheets 44^b of elastic or yielding material as well as felt, rubber and the like, it being understood that the corrugated formation of the

sheets or segments 44^a will render them of 65 greater rigidity than a flat strip or sheet but the yielding sheets 44^b will permit of the angular movement of the segments 44^a as will be apparent. In this construction, I also preferably provide at least one side 70 edge of the segments 44^a with a plurality of tooth-like projections 44^c which are adapted to imbed themselves into one of the parts to be coupled together by the device 44. This will operate to retain the segments 75 against displacement and will insure a more positive securing and coupling of the parts.

In Fig. 21 of the drawing, I have shown another modification wherein a lock strip 45 composed of rubber or other yieldable 80 material is provided on one side face with a plurality of grooves 45^a forming projecting ribs or teeth 45^b having comparatively straight sides 45^c upon which are placed segments 46 of substantially rigid material, 85 which set in the grooves 45^a and are provided with extending flanges 46^a at the base of said grooves and extending onto the beveled or inclined faces of the ribs or teeth 45^b.

90 In Fig. 22 of the drawing, I have shown a lock device 47 consisting of a molded block or body of rubber or other suitable material, in which is imbedded strips or segments 48 of metal, fibre or other rigid 95 material, said segments being preferably arranged at a slight inclination to a vertical line extending through the device 47 as seen in the drawing. Disposed between the segments 48 are apertures or recesses 47^a which 100 permit of a greater flexing of the segments 48 in the device 47.

105 It will be understood that in all forms of lock device herein shown and described, the same are placed and supported within and between two parts to be coupled together thereby, said parts being constructed to suit the adaptation of the lock strip or device, and said strip will be constructed to suit and provide the required tensile 110 strength in the coupling of said parts. While I have shown certain combinations of elements or materials in the different arrangements and modified forms of lock devices, it will be understood that these arrangements may be remodified in accordance 115 with the suggestions herein outlined, and various other changes in and modifications of the lock device and the method of its use for the purposes stated, may be made within the scope of the appended claims without departing from the spirit of my invention or sacrificing its advantages.

120 It will also be understood that the lock strip or body and/or its segments or flexing parts may be treated with any suitable material which will act as a coating to give greater rigidity to the body, or as an at-

tractive coating, and especially in treating paper, cardboard, fibre, rubber and similar materials, and in some instances, tar, pitch, and similar waterproofing substances 5 may be used. However, it will be apparent that other materials in the form of paints, varnishes, lacquers and the like may be employed.

Having fully described my invention, 10 what I claim as new and desire to secure by Letters Patent, is:—

1. A lock and coupling device of the class described consisting of a flat, strip-like body having a plurality of segments composed of 15 rigid material, said segments being arranged side by side with the edges thereof exposed at opposite sides of said body.

2. A lock and coupling device of the class described consisting of a body having a plurality of segments composed of rigid material, said segments being arranged side by 20 side with the edges thereof exposed at opposite sides of said body, and other segments of yielding material interposed between said 25 first named segments.

3. A lock and coupling device of the class described comprising a flat, strip-like body having straight surfaces, one surface of which is provided with a plurality of segments 30 arranged side by side and said segments being adapted to flex and be placed under compression in coupling two parts together by said body.

4. A device for securing two parts together 35 consisting of a strip having straight sides disposed between adjacent straight surfaces of said parts, and said strip comprising segmental portions angularly disposed with reference to said parts when 40 coupled together thereby.

5. A device for securing two parts together consisting of a strip having straight sides disposed between adjacent straight surfaces of said parts, said strip comprising 45 segmental portions angularly disposed with reference to said parts when coupled together thereby, and the strength of said segmental portions being such as to withstand the stress and strain to which the parts 50 coupled together thereby are subjected to prevent separation of said parts.

6. A device for securing two parts together 55 consisting of a flat body having straight sides disposed in a space arranged between straight, adjacent and substantially parallel surfaces of said parts, the depths of said body being greater than the depth of said space, said body having flexing portions whereby in coupling said parts together, said body is wedged between said adjacent surfaces and the flexing portions of said body assuming an inclined position

with reference to a plane at right angles to the adjacent surfaces of said parts.

7. A device for securing two parts together 65 consisting of a flat body having straight sides disposed in a space arranged between straight, adjacent and substantially parallel surfaces of said parts, the depth of said body being greater than the depth of said 70 space, said body having flexing portions whereby in coupling said parts together, said body is wedged between said adjacent surfaces, the flexing portions of said body assuming an inclined position with reference 75 to a plane at right angles to the adjacent surfaces of said parts, and said body being composed of sections disposed angularly with reference to each other.

8. A lock and coupling device of the class 80 described comprising a flat, strip-like body of yielding material adapted to be wedged between substantially parallel and straight surfaces of two parts to be coupled together thereby, and said body having segmental 85 portions adapted to be moved into an inclined position with reference to the surfaces of said parts coupled together by said body.

9. A device for coupling two parts together 90 consisting of a laminated body of yielding material, said body being arranged between the adjacent faces of said parts with the edges of the laminations engaging the walls of said parts.

10. A device for coupling two parts together 95 consisting of a body of yielding material adapted to be positioned between said parts, said body being composed of a plurality of independent metallic strips arranged with the side edges of said strips 100 exposed at opposite sides of said body.

11. A device for coupling two parts together 105 consisting of a body of yielding material adapted to be positioned between said parts, said body being composed of a plurality of independent metallic strips arranged with the side edges of said strips exposed at opposite sides of said body, and one side edge of said strips being segmental. 110

12. A device for coupling two parts together 115 consisting of a body of yielding material adapted to be positioned between said parts, said body being composed of a plurality of independent metallic strips arranged with the side edges of said strips exposed at opposite sides of said body, and bodies of rubber interposed between the adjacent sides of said strips.

In testimony that I claim the foregoing as 120 my invention I have signed my name this 9th day of September, 1927.

HARRY E. SIPE.
